UNITED STATES PATENT OFFICE.

CLAIREE WHITNEY, OF SAN FRANCISCO, CALIFORNIA.

DESIGN FOR A BADGE.

47,514.

Specification for Design. Patented June 22, 1915.

Application filed April 26, 1915. Serial No. 24,165. Term of patent 3½ years.

To all whom it may concern:

Be it known that I, CLAIRE WHITNEY, a citizen of the United States, residing at San Francisco, in the county of San Francisco and State of California, have invented a new, original, and ornamental Design for Badges, of which the following is a specification, reference being had to the accompanying drawing, forming a part hereof.

Figure 1 is a front view of a badge, showing my new design, and Fig. 2 is a side elevation of the same.

I claim:

The ornamental design for a badge, as shown.

CLAIREE WHITNEY.

Witnesses:

ROBERT R. RUSS,
ALFRED D. MARTIN.
